UNITED STATES PATENT OFFICE.

PAUL ACHILLE JOSEPH COUSIN, OF LOOS-LEZ-LILLE, FRANCE.

GAS-PRODUCER.

1,246,888.

Specification of Letters Patent. Patented Nov. 20, 1917.

Application filed October 16, 1912. Serial No. 726,038.

To all whom it may concern:

Be it known that I, PAUL ACHILLE JOSEPH COUSIN, citizen of the Republic of France, residing at 84 Rue Faidherbe, Loos-lez-Lille, 5 Nord, in the Republic of France, have invented new and useful Improvements in Gas-Producers, of which the following is a specification.

This invention has for its object to produce an improved gas producer capable of burning all kinds of fuel and of producing gas of varying compositions.

A characteristic feature of this gas producer is that a central air distributer the orifices of which are completely covered by the water in the ash pit, is combined with a truncated conical producer chamber of downwardly flaring shape with the object of rendering spongy and easily breakable 20 the layer of clinkers that is formed at the base of the charge of coal in the producer chamber, for the purpose of facilitating its breakage and descent into the ashpit.

An embodiment of this invention is illustrated by way of example in the accompanying drawings in which:

Figure 1 is a vertical section of the gas producer on the line A—A of Fig. 3,

Fig. 2 is a view of a detail, and

Fig. 3 is a horizontal section on the line B—B of Fig. 1.

As shown the improved gas producer comprises a truncated conical producer chamber *a* of downwardly flaring shape surrounded by a jacket of refractory brick-work *b*, a non-conducting filling of sand *d* and a cylindrical metal casing *c*. This casing *c* extends into the ashpit *e* and may form a liquid seal for internal pressures not exceeding a certain limit. Beyond this limit a movable bell *f* is employed which is adapted to be raised and lowered at will and which when immersed in the water in the ashpit *e* forms also a liquid seal, that shuts off all communication between the interior 45 of the producer chamber with the atmosphere.

A liquid seal between the casing *c* and the upper part of the bell *f* also helps to insure 50 air-tightness. For this purpose the upper part of the bell *f* is bent over and extended into a channel *l* fixed to the casing *c* which is kept filled with water.

The actuation of the movable bell *f* may 55 be effected by means of counterweights *g* and chains *h* passing over pulleys *i* carried

by supports fixed to the casing *c* or by any other suitable mechanism.

The ashpit *e* has internally a conical or parabolic shape or the shape of another surface of revolution suited to each kind of fuel. It ends at the middle of its lower part in a trench *k* into which the ashes and clinker fall and whence these are removed mechanically by a chain of buckets *7* or any other mechanism for raising the ashes to ground level. A distributer *m* may be provided for filling the buckets.

The ash hoist *7* is located as shown, in a trench *5* into which the water stands at the same level as in the ashpit *e*. The entire chamber *a* is supported on pillars *n* which may be for instance of cast iron, resting on blocks or piers of brickwork. The pillars *n* carry a metal ring *o*, for instance of cast iron which in its turn supports the entire upper part of the gas producer.

A special device allows of blowing in air into the chamber beneath the level of the water in the ash pit. It comprises a cast iron cone *p* arranged in the middle of the ashpit. This cone is extended at its upper part to form a chamber *q* provided with an inlet *r* into which is jointed the air supply pipe *s*. The upper part of this chamber *q* has a seating *t* to receive the distributing cap *u* pierced at a single level or at several different levels with peripheral apertures *v* for the exit of the air. These apertures may be horizontal or inclined.

The air distributer *u* is removable and may be replaced by another having apertures situated on different levels. By means of a set of these distributers the air can be blown into the chamber at any desired height according to the rate of working of the producer and the kind of fuel used. In all cases the distributer has its apertures *v* situated below the level of the water in the ashpit.

The gas producer is provided at its upper part with charging boxes, stoking holes and gas exit orifices in the usual manner.

The use of an air distributer having its apertures immersed insures that the injected air shall carry a considerable quantity of water which when projected upon the clinker that is in course of formation will render the said clinker spongy and friable so that the scaffolding *8* formed by the clinker at the base of the producer chamber 110 will have but little cohesion and can be easily broken away in the cleaning operation

by means of an implement introduced through the upper apertures provided for this purpose.

Moreover as the scaffolding is broken away it descends naturally to the bottom of the producer chamber owing to the downwardly flaring shape of the said chamber. This descent is further facilitated by the circumstance that the clinker which has been 10 rendered friable does not adhere very firmly to the sides of the chamber. Before proceeding to break away the scaffolding, the top layer of clinker 10 in the ashpit is removed as usual in order to allow the scaffolding to descend.

The improved apparatus has the advantage of being capable of being worked at a great variety of rates as regards the temperature, the composition of the gas, the pressure 20 of the air, the breaking up of the clinker and its removal from the ashpit, so that it can be worked with any kind of fuel.

The greater or less intensity in the rate of working is regulated both by the pressure 25 of the air and the proportion of water which is carried into the producer chamber by the air. The modification in the pressure is permitted by means of the variable level liquid seal, and the proportion of water carried 30 over by the air varies with the distributor that is used, because the distance of the apertures v from the water level in the producer chamber regulates the amount of water vapor that is formed since the air is 35 thus caused to pass through a greater or less depth of water.

The clinker may be removed through the annular space w comprised between the wall j of the ashpit and the base of the casing e , 40 the bell f being then completely raised.

The clinker may be cleaned out periodically by removing it through the bottom of the ash-pit e by means of the chain of buckets 7. The vertical sectional contours of the 45 cone p , the ashpit e and the producer chamber a must be designed according to the kind of fuel used, so as to cause the clinker to move down in layers parallel to the vertical sectional contour of the scaffolding 8, in 50 order that the mass of fuel shall be uniformly pervious to air at all points.

The cleaning out of the clinker may also be effected in a continuous manner, for instance in the case of fuel containing a large 55 proportion of ash. In such a case the chain of buckets 7 is run continuously at a low speed.

In case of a stoppage, the gas producer can remain for several days without the fire 60 going out, ready for working again, pro-

vided that it is supplied with a small quantity of air.

The means to this end comprises a duct x provided with a cock or valve y of any kind extending into the producer chamber and opening at a point above the level of the water therein. In order that the upper part of this duct shall not become choked with ash, clinker or slag, the said part may be closed and perforated with small holes 4 in 70 its periphery. On opening the cock y air from this duct is allowed to enter the producer chamber in a small but sufficient quantity for preventing the fire from going out. This means also prevents the formation of 75 a mixture of gas and air in starting and the consequent risk of explosion.

Having now described my invention what I claim as new and desire to secure by Letters Patent is:—

1. In a gas producer, the combination of an ash pit adapted to contain a body of liquid, a conical producer chamber having its base resting upon and communicating with said ash pit, a casing surrounding said chamber and having its lower edge projecting beyond the same into the liquid in the ash pit, a liquid-filled channel carried by said casing adjacent its lower edge, a movable bell having a portion thereof projecting into the liquid in the ash pit and an angular portion resting in said channel, and means in the ash pit through which a moist air-blast may be delivered to said producer chamber.

2. In a gas producer, the combination of an ash pit adapted to contain a body of liquid, a series of pillars in said ash pit, a conical producer chamber having its base supported by said pillars and in open communication with said ash pit, a casing surrounding said chamber and having its lower edge extended beyond the chamber and into the liquid in the ash pit, a liquid-filled channel carried by said casing adjacent its lower edge, a movable bell dipping into the liquid in the ash pit and having an upper angular portion resting in said channel, an air-directing cone supported in said ash pit below the normal liquid level therein, and an air distributing cap removably carried by said cone.

In testimony whereof I have signed my name to this specification in the presence of two subscribing witnesses.

PAUL ACHILLE JOSEPH COUSIN.
